UNITED STATES PATENT OFFICE

95,385

DESIGN FOR A FOOD CONTAINER UNIT

Lewis H. Scurlock, Chicago, Ill.

Application February 11, 1935, Serial No. 55,348

Term of patent 14 years

To all whom it may concern:

Be it known that I, Lewis H. Scurlock, a citizen of the United States, and resident of Chicago, in the county of Cook and State of Illinois, have invented a new, original, and ornamental Design for a Food Container Unit, of which the following is a specification, reference being had to the accompanying drawings, forming a part thereof.

Fig. 1 is a plan view of a food container unit showing my new design.

Fig. 2 is a side elevation of said unit.

Fig. 3 is a plan view of one of the containers shown in the group shown in Figs. 1 and 2 of the drawings.

Fig. 4 is a vertical cross section of one of the round covers shown in Figs. 1 and 2 of the drawings.

Fig. 5 is a front elevation of the container shown in Fig. 3 of the drawings.

Fig. 6 is a side elevation, looking in a different direction, of the said container shown in Fig. 3 of the drawings.

The device of my design comprises the several container elements and covers therefor shown in solid black lines in the drawings, combined with a base shown in dotted lines. The dominant features of the design are shown in the solid black lines. The ornamental feature of the design comprises the particular shape and arrangement of the containers and covers as shown.

I claim:

The ornamental design for a food container unit, as shown and described.

LEWIS H. SCURLOCK.
